DESIGN FOR AN ILLUMINATING DEVICE FOR INSTRUMENTS

David I. Critoph, Buffalo, N. Y., assignor to Spencer Lens Company, Buffalo, N. Y., a corporation of New York

Application February 20, 1940, Serial No. 90,385

Term of patent 14 years

To all whom it may concern:

Be it known that I, David I. Critoph, a citizen of the United States, residing at Buffalo, in the county of Erie and State of New York, have invented a new, original, and ornamental Design for an Illuminating Device for Instruments, of which the following is a specification, reference being made to the accompanying drawing, forming a part thereof.

Fig. 1 is a perspective view of an illuminating device for instruments showing my new design;

Fig. 2 is a top or plan view thereof with the base omitted for convenience of illustration; and Fig. 3 is a front elevational view thereof.

In the drawing the dominant features of my design are shown in full lines.

I claim:

The ornamental design for an illuminating device for instruments, substantially as shown and described.

DAVID I. CRITOPH.
